UNITED STATES PATENT OFFICE.

WILLIS C. MERRILL, OF BOSTON, MASSACHUSETTS, ASSIGNOR OF ONE-HALF TO THE MERRILL PROCESS COMPANY, A CORPORATION OF MASSACHUSETTS.

HEATING APPARATUS.

1,278,070.

Specification of Letters Patent.

Patented Sept. 3, 1918.

Application filed November 19, 1915. Serial No. 62,411.

To all whom it may concern:

Be it known that I, WILLIS C. MERRILL, a citizen of the United States, and a resident of Boston, in the county of Suffolk and State of Massachusetts, have invented certain new and useful Improvements in Heating Apparatus, of which the following is a specification.

My invention relates to a new and useful heating apparatus especially adapted for the heating of asphaltic, bituminous or like materials where a high temperature is required to properly liquefy said materials to produce sufficient limpidity to cause said materials to flow freely.

One object of my invention is to produce a new and useful improved fuel oil heater adapted for use in connection with my improved heating apparatus.

Another object is to provide for the relief of undue pressure exerted by the pump in circulating the heating liquid medium due to a cold mass of the circulating heating liquid or oil in the heating coil at the time of starting and heating and before the said heating oil is raised to such a temperature as to flow freely for heating the entire mass of the material under treatment.

These and other objects are carried out by the apparatus herein described and shown in the drawings.

In the accompanying drawings which illustrate a construction embodying my invention:

Fig. 1 is a side elevation of the apparatus with the improved fuel oil heater partly broken away to illustrate the interior arrangement of the coil in the heater.

Fig. 2 is a side elevation of the tank or receptacle for holding the material to be treated, and is shown as broken away to illustrate the heating coil for liquefying the material within the tank or receptacle containing the material under treatment and also showing my improved liquid draw off device for the liquefied material.

Fig. 3 is a plan view of the tank or receptacle in which the material is treated or liquefied partly broken away to show the heating coil and also the improved fuel oil heater broken away to illustrate its interior construction and arrangement, with the circulating pump and other coöperating parts.

Fig. 4 is a vertical cross section through the fuel oil heater.

Fig. 5 is a sectional detail view with the side of the fuel oil heater broken away to illustrate the arrangement of the heating coil through which the heating liquid medium flows for heating the material under treatment in the tank or receptacle.

Like letters of reference refer to like parts throughout the several views.

In carrying out my invention as applied to asphaltic, bituminous or like materials the material is introduced into a suitable tank or receptacle B, through a nozzle B' closed by a suitable cover B², from a stationary storage or supply tank in which the material is stored at from about 125° F. to 70 200° F. or more. Or if desired the material for treatment or liquefaction may be introduced in a solid or semi-liquid form into the tank or receptacle B without preliminary heating and gradually heated to the melting 75 point in the tank or receptacle B, as herein-after described, and then raised to the required temperature in the tank, thus avoiding the use of the preliminary heating storage or supply tank. After the material has 80 been introduced into the tank or receptacle B, the inlet nozzle B' is closed after the asphaltic, bituminous or like material has reached the desired height in the tank or receptacle B.

From a suitable source, as the expansion tank L and feed pipe M, a pump or other circulating device K receives a liquid medium, as a suitable mineral oil, having a higher boiling point than 212° F. and this heating liquid medium is circulated and heated to raise the temperature of the material in the tank or receptacle B to liquefy the same to facilitate its easy flow. This pump K forces this heating liquid medium 90 through the pipe O² into the pipe D which connects with the heating coil C located in the fuel oil heater A and this coil C extends to the opposite end of the fuel oil heater A, as shown, and leaving this opposite end connects through the pipe S with the heating coil W which is coiled and located in the tank or receptacle B and leaves the tank B at its opposite end where it connects with a pipe R connected to the pipe O' leading to 105 the circulating heating oil pump K operated by any suitable mechanism. Suitable hand valves N, E and Q are located respectively in pipes M, O² and R for use as desired.

This heating liquid medium is kept in constant circulation through this closed circulating conduit consisting of the pipes O^2 and D, the coil C, connecting pipe S, the coil 5 W and the pipes R and O' back to the circulating heating oil pump K and brings the temperature of the contained asphaltic, bituminous or other material to about 300° F. to 400° F. The burner T receives a suitable supply of gas and air through the pipes U and V which are controlled by hand or automatically if desired to regulate the same. The heating coils C in the fuel oil heater A are wound as closely together as expedient, one-quarter to one-half inch apart, and in slight contact with the asbestos lining C' arranged within the two shells forming the fuel oil heater A and prevents the radiation of heat from the interior of the fuel oil 10 heater A, and this arrangement of the heating coils C brings into contact with the products of combustion extended heating surfaces through which the heating liquid medium circulates and by slightly spacing 15 the coils the excess of heat of the products of combustion circulates around the coils so that all the heating surface possible is in contact with the heat of the products of combustion. By arranging the coils of the 20 heating liquid coil C within the heater close together the heating liquid medium circulating through said coils rapidly absorbs the heat units of the products of combustion as rapidly as possible with as little loss 25 through waste gases as possible.

As the temperature of the escaping gases from the stack A' will always be in excess of the temperature to be attained by the heating liquid medium within the circulating 30 coils, for instance, if a temperature of about 500° F. was desired in the circulating heating liquid medium then the temperature of the escaping gases should not be less than about 550° F., and in practice in burners 35 used today by the applicant the temperature of the heat generated primarily by the burner T is in excess of 2500° F., which intense heat requires rapid absorption of the heat units by the circulating liquid heating 40 medium and rapid removal by the pump, with good insulation, as the asbestos C', to prevent destruction of the heater shell or container and to prevent radiation and the loss of heat and thereby produces an economy 45 in the utilization of the heat units from the products of combustion in the fuel oil heater A.

The pipe F leads from the pipe O^2 at the joint O to the top of the expansion tank L 50 through the pipe I for the purpose of providing a short circuit of the circulating heating liquid medium or oil from the pipe O^2 to the expansion tank L on the delivery or force side of the circulating pump K 55 upon the obstruction of the normal circula-

tion of the heating liquid medium or oil from any cause. This circulation of the heating liquid medium through the pump K, the expansion tank L and back and through the pump K is controlled by opening the valve G normally closed, and this short circuiting of the heating liquid medium or oil through and around the pump is to meet a condition of pump pressure which might arise from any cause, for example, to a cold mass of the circulating heating medium or oil in the heater at the starting of the apparatus and before the circulating heating liquid medium or oil is raised to such a temperature as to flow freely 70 under the forced circulation by the pump K for heating the entire mass within the receptacle B. Upon the normal circulation being established, due to sufficient reduction in pressure, the valve G is closed so as to 75 close the short circuiting of the heating oil through and around the pump and force the circulating heating liquid medium through the closed conduit to absorb the heat units in the heater and distribute the same uniformly to the material under treatment in 80 the tank B.

The pipe J connects with the pipe F and through the pipe I communicates with the top of the expansion tank L and affords 90 relief automatically of any excess pump pressure arising at any time in the apparatus, as above stated, by operating the automatic relief valve H of any desired construction and set at a pressure within safety 95 to operate for any of the reasons above stated to cause the short circuiting of the heating liquid medium or oil through and around the pump until the normal circulation of the heating liquid medium or oil 100 through the closed circulating conduit is re-established, when the relief valve H automatically closes owing to the drop of the pump pressure which may have arisen from any cause interfering with the normal circulation 105 of the circulating heating liquid medium or oil.

By providing these two safety relief devices to relieve the pump pressure there is assured the freedom of possibility of accident 115 from disruption or injury to the pump or other parts of the apparatus, as in the event of one of the valves being out of order, the other can be operated to relieve the pump pressure and avoid accident.

The circulating pump K or other circulating mechanism is employed to keep this heating liquid medium in constant motion and in its transit it is brought in contact with high temperatures in the fuel heater A 125 such as would be produced by burning fuel oil, kerosene, gas or other heat producing material, and the circulating heating medium is advanced or pushed forward by the circulating pump K and the heat units 130

stored in this medium are transferred to the mass of asphalt or like material of lower temperature contained within the tank or receptacle B. The advantage of this continuous circulation consists in using a liquid medium that does not condense at a low temperature and does not concentrate the heat applied so as to carbonize the material under treatment because the heat units stored in this medium are under control and the temperature of the liquid heating medium at no time reaches a point that injures the integrity of the contained mass in the tank. Any suitable hand operated control or thermostat may be used to regulate the degree of temperature that may be desired.

Now by the use of this circulating oil heating fluid, a minimum pressure, say 5 to 10 lbs. per square inch, due to the friction of the heating fluid passing through the pipes and not due to the temperature of the circulating heating fluid, is maintained in the circulating coils, all the difficulties encountered in the use of steam are obviated and the danger of foaming is also entirely removed, and in the event of a leak occurring, the oil so escaping from the coils readily mingles and unites with the asphaltic material and does not cause foaming. Furthermore there is no pressure within the interior of the tank containing asphaltic material during the heating of this material by this circulating oil for the reason that the heating medium is all contained in a tight circulating coil and is kept circulating, and furthermore the oil does not expand except through the expansion tank N provided for it on the exterior of the tank containing the asphaltic material. Now when the coil is full of circulating oil, any expansion of this oil in the conduit or coil is provided for by the expansion tank L into which the expanded oil flows through the pipe M, and relieves the pressure in the system, so that the disruption or injury to the pump or other part of the apparatus is avoided and constant supervision unnecessary, and this oil circulating produces uniform distribution of heat.

By connecting the feed pipe M to the suction side of the pump K, expansion of the circulating heating liquid medium or oil is provided for without interfering with the circulation of the same, and any lack of circulating heating oil is supplied by the tank L to replenish from time to time the circulating heating liquid medium or oil if necessary, as the expansion, if any, of the circulating oil passing up through the pipe M does not interfere with the feeding of the heating oil to the closed conduit for the circulating oil on the suction side of the pump K. If, on the other hand, the feed pipe M from the expansion tank L were connected on the delivery or force side of

the pump K, any excess pressure due to the pump that might occur would tend to drive the circulating heating liquid medium or oil up through the normally open feed pipe M into the expansion tank L rather than through the closed conduit for the circulating heating oil, and also prevent any feeding of the heating oil from the tank L through the pipe M to the closed conduit for the circulating of this circulating heating liquid medium or oil.

In the continuous circulation of this heating fluid medium, the losses usually attendant upon circulating steam do not occur, the loss being negligible in this circulating heating fluid medium, as condensation does not take place and the heat units imparted to the circulating heating fluid medium are given up directly when brought in contact with the material to be heated. No provision in this system of circulation is necessarily made as with steam to dispose of the condensation, and this circulating heating fluid medium being a non-elastic liquid differs from a condensable elastic fluid like steam and may be used over and over again for heating the material under treatment. By this forced circulation of the heating liquid medium by the pump, the heat units are uniformly distributed to the material under treatment, and further by this rapid circulation of this heating liquid medium, new surfaces of the heating liquid or oil are continuously presented to the heater and by this forced circulation the heated liquid or oil is rapidly removed from the heater and thereby prevents carbonization of the heating liquid medium in the heater and the consequent crystallization of that portion of the heating oil conduit located in the heater.

This circulating heating oil used as a heating fluid medium in this system is similar to that used in the apparatus shown in my co-pending application Ser. No. 831,922, filed April 15, 1914, and has a boiling point above 212° F. and a carbonizing point higher than the temperature required to properly liquefy the material, so that in its circulation it imparts to the material under treatment heat at high temperatures without gasifying, as in the case of steam, and to impart temperatures higher than is practicable with steam, thereby enabling the said circulating heating oil medium to be heated to high temperatures without carbonization and the consequent deposit of carbon on the inner surfaces of the conduit. Such deposits of carbon on the interior of the heating conduit or coil prevent the easy flow of the heating oil and the ready transmission of heat to the material under treatment on account of the obstruction in the conduit of carbon deposits and of the increased density of the circulating heating fluid by the form-

ing of carbon in the circulating heating oil, and the integrity of the heating coil or conduit by such deposits of carbon is endangered because the heat generated by the 5 external heater is not readily accepted by the circulating heating oil medium and thereby causes a burning or crystallizing of the heating conduit or coil, all of which difficulties are obviated by the use of a 10 circulating heating oil whose carbonizing point is higher than the temperature required for the proper liquefying of the material under treatment.

The temperature of the circulating heating 15 fluid medium when in use averages about 400° F. to 500° F. which gives approximately a temperature of about 300° F. to 400° F. to the asphalt, low gravity oils or bituminous materials under treatment, 20 and this temperature is high enough to produce a sufficient lippidity in any known form of asphalt or like materials to cause them to flow freely before the carbonizing point of the asphalt or like materials or of 25 the circulating heating liquid medium has been reached, so that the integrity of the materials under treatment is not destroyed, nor is there any loss or deterioration of the circulating heating liquid medium.

30 The metallic shell of the fuel oil heater A may be of thin and light metal because of the advantage possessed in the lesser amount of metal to store any unabsorbed heat and thereby radiating to the coils containing the 35 circulating medium after the apparatus is shut down, as it is desirable to have the apparatus cool off as rapidly as possible when not in use, and thin and light metal may be used in my improved heater for the reason 40 that the rapidly circulating heating liquid medium or oil passing through the coils C in the fuel oil heater rapidly absorb the heat units of the products of combustion and carry off the same, and this rapid absorption is continued by reason of new surfaces 45 of the heating liquid medium being continuously forced through the coils of the heater by the circulating pump.

In installations where insulating material 50 like fire brick or heavy cast iron containers are used the effect of heating these containers to a high degree during the operation of the apparatus is to store heat which later on when used with an apparatus of 55 this character would radiate and heat the coils in the fuel oil heater to the injury of the circulating heating liquid medium contained in the heating coils should the system cease to operate or if shut down at the end 60 of the work and the fuel oil heater would not therefore readily cool off.

By my arrangement of a heating coil with an asbestos covering on the exterior thereof, a thin and light shell may be used which 65 not only prevents radiation of heat to the

atmosphere, but avoids the storage of heat therein and the consequent giving off of the same after the apparatus is closed down or the machine should be stopped for some unavoidable reason.

70

In this fuel oil heater A the convolutions of the heating coil C are so arranged with respect to the burner T and to one another that their surfaces absorb the heat generated by the burner T, and the exterior of this heater A is insulated by the absorption of the heat units within said heater, and the interior asbestos lining C' assists in insulating the heater and prevents radiation of the 80 heat from within said heater to the atmosphere. This fuel oil heater A consists of a large chamber open at one end for the burner T and permits ready expansion of the burning gases and facilitates the absorption of the heat units created, while the 85

75

other end of the heater A is reduced in diameter, with the coils C correspondingly reduced to fit therein, and extends close up to the outlet stack A', while the other end of the heating coils C extends as close up as is practical to the mouth of the heater where the flame T' at its greatest heat enters the heater from the burner T so that the heat entering is at once taken up by the lining of coils through which the heating circulating 90 liquid or oil is circulated. This reduction in diameter of the fuel oil heater A causes a further impingement of the other burning gases and more rapid circulation of the heat units through the heater which heat units 95

95

as they pass through the said heater are taken up and absorbed by the circulating oil within the heating liquid coils C, and this heating liquid or oil, due to its rapid forced circulation by the pump, is kept in constant rapid circulation bringing new surfaces of the heating oil continuously into contact with the high heat of the heater and preventing carbonization of the circulating liquid or oil within the heating coils and thereby further preventing the crystallization of the heating coils within the heater as the circulating heating liquid or oil is moved so rapidly that it does not reach a 100 temperature where it deposits carbon in the 105 heating coils, especially the coils in the fuel oil heater A.

110

In this apparatus the circulating heating liquid medium or oil flows, as indicated in the drawings, in an opposite direction to the products of combustion in the heater and the advantages of this counter current heating are that the circulating heating liquid medium or oil to be heated leaves the heater at the highest temperature and is directly in 115 contact with the highest temperature of the products of combustion from the burner and where the circulating heating liquid medium or oil to be heated enters the heater it is at 120 its lowest temperature and utilizes the heat 125

110

115

120

125

130

in the products of combustion which is also at its lowest temperature.

In the operation of the draw off illustrated in Fig. 2, when the material has reached the proper degree of temperature to cause the asphalt or other like material to flow freely the valve Z is opened and the hottest material from the top of the tank passes down through the shell X and out through the pipe Y.

After the material at the top of the tank has been drawn off in this manner the handle X⁴ is operated to raise the inner shell X' to allow the liquefied asphalt or other material in the bottom of the tank to flow through the perforations X² in the bottom of the shell X and out through the pipe Y. After the material has been drawn off as desired the valve Z is closed and the parts are moved to their normal positions.

Having thus described the nature of my invention and set forth a construction em-

bodying the same, what I claim as new and desire to secure by Letters Patent of the United States, is:

The combination with a cylindrical tank having a supply inlet and an outlet, and a cylindrical heat confining chamber arranged parallel to said tank, means to supply heat to said chamber, of a conduit having a pair of connected coils located respectively within said tank and within said chamber, a connecting portion of said conduit between said coils having a pump to circulate liquid, an expansion tank communicating with said conduit by pipes at both sides of said pump to permit of circulation against static pressure in one of said pipes, and a liquid medium filling said conduit and pipes and adapted when heated to be circulated by said pump.

In testimony whereof, I have signed my name to this specification.

WILLIS C. MERRILL.
